(57) **CLAIM**

The ornamental design for a portable electric band saw, as shown and described.

DESCRIPTION

FIG. 1 is a perspective view of top, front, and left side of a portable electric band saw showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a perspective view of bottom, rear, and right side view thereof; and,

FIG. 9 is an alternate perspective view of the portable electric band saw of FIG. 1 shown in an environment of use.

The broken lines and the areas within the broken lines are included for the purpose of illustrating portions of the "article" and form no part of the claimed design.
